INSULATING STRUCTURE AND METHOD OF
ASSEMBLINGWilliam G. Spiegelhalter, Erie, Pa., assignor to
General Electric Company, a corporation of
New York

Application December 23, 1950, Serial No. 202,528

15 Claims. (Cl. 220—15)

1

My invention relates to spaced wall cabinets and more particularly to insulating structures therefor and to method of assembling such insulating structures.

An insulating structure composed of a plurality of spaced sheets of a material of high reflectivity, such as aluminum foil, has previously been proposed. However, in many spaced wall structures, such as household refrigerators and home freezers, the outer wall is flanged inwardly adjacent the access opening, complicating the problem of assembly within this outer wall of an inner wall or liner and a surrounding insulating structure of the above type. By my invention, I provide a simple arrangement whereby an insulating structure utilizing spaced sheets of a pliant material of high reflectivity may be pre-assembled on the liner, partially collapsed to facilitate insertion through the opening in the outer wall, and then expanded to completely fill the space between the inner and outer walls.

It is an object of my invention to provide an improved insulating structure which facilitates assembly thereof within a spaced wall cabinet.

It is a further object of my invention to provide an improved arrangement for facilitating assembly within a spaced wall cabinet of an insulating structure which includes spaced sheets of a material of high reflectivity.

It is a further object of my invention to provide an improved method for facilitating assembly of such insulating structures within a spaced wall cabinet.

Further objects and advantages of my invention will become apparent as the following description proceeds and the features of novelty which characterize my invention will be pointed out with particularity in the claims annexed to and forming a part of this specification.

In carrying out the objects of my invention, concentric envelopes of a pliant material of high reflectivity are maintained in spaced relationship by hollow inflatable spacers. Air is withdrawn or allowed to leak from the spacers to partially collapse the insulating structure for facilitating insertion of this structure within the narrowed opening of the outer wall, and air is supplied or allowed to return to the spacers to inflate the spacers for expanding the structure to fill the space between the inner and outer walls.

For a better understanding of my invention, reference may be had to the accompanying drawings in which Fig. 1 is an elevation view, partly in section, of a refrigerated cabinet embodying my invention; Fig. 2 is a sectional plan view taken

2

along the line 2—2 in Fig. 1; Fig. 3 is a view of a portion of Fig. 2 showing the insulating structure in a partially collapsed position; Fig. 4 is a view similar to Fig. 1 showing the insulating structure being inserted within the cabinet; Fig. 5 is an enlarged view showing details of a spacer; Fig. 6 is a view taken along the line 6—6 of Fig. 5 and further illustrating portions of the insulating sheets; and Fig. 7 is a view, slightly reduced, showing a portion of one of the individual insulating sheets employed.

Referring to Figs. 1 and 2, there is shown a cabinet 1 of the spaced wall type including an outer wall 2 and a spaced inner wall or liner 3. The liner 3 defines a storage compartment 4. The access opening of the compartment 4 is closed by a lid 5. The outer wall 2 is flanged inwardly adjacent the access opening, as indicated at 6, and the inner wall 3 is flanged outwardly adjacent the access opening, as indicated at 7. The space between the inner and outer walls adjacent the access opening is closed by a breaker strip 8 of a material of low heat conductivity.

In order to maintain the desired temperature difference between the ambient temperature and that to be maintained within the compartment 4 an insulating structure 9 is arranged between the inner and outer walls of the cabinet. This insulating structure includes a plurality of concentric envelopes 10, each of which is composed of a plurality of sheets of a pliant material of high reflectivity, such as aluminum foil. To secure the maximum insulating value, it is necessary that the successive layers or envelopes of aluminum foil be maintained in spaced relationship, and to accomplish this result, a plurality of spacers 11 are provided. In the specific cabinet illustrated, the inner and outer walls are of generally rectangular cross-section and the envelopes 10 are similarly of rectangular cross-section. With this arrangement, the spacers 11 are positioned at the corners of the inner and outer walls and extend diagonally therebetween, the inner end 11a of each spacer being secured in any suitable manner, as by gluing, to the corresponding corner of the inner wall 3. In addition to the corner spacers 11, one or more similar intermediate spacers can be employed, arranged perpendicular to the inner and outer walls, depending on the size of the cabinet.

Since the outer wall 2 is flanged inwardly in the area of the access opening of the cabinet, as indicated at 6, the cross-sectional area of the opening available for insertion of the inner wall liner 3 and the surrounding insulating structure

9 into the cabinet is less than the cross-sectional area of the interior of the major portion of the outer wall 2. Since, in the assembled cabinet, it is desirable that the envelopes 10 be equally spaced throughout the distance between the inner and outer walls, a problem in assembling the inner wall 3 and the insulating structure through the smaller opening available in the outer wall is presented. It is more convenient and more satisfactory to pre-assemble the insulating structure on the inner wall 3 before insertion in the cabinet. I accomplish the result of permitting such pre-assembly and at the same time facilitating insertion of the assembled insulating structure and liner through the opening in the cabinet while still achieving a final cabinet structure in which the insulating structure fills the space between the inner and outer walls by making the spacers 11 in the form of hollow inflatable elements.

Details of the construction of the spacers 11 are shown in Figs. 5 and 6. As there illustrated, each of the spacers 11 is made of a flexible material, such as rubber, molded to provide a hollow inflatable structure. A plurality of spaced slots or recesses 12 are also molded in the spacers 11 to provide for receiving the aluminum sheets of which the envelopes 10 are formed. In the form illustrated each of the envelopes 10 is formed from four individual aluminum sheets 13, such individual sheets being shown in detail in Fig. 7. The sheets 13 are formed with slots or recesses 14 at the ends, these slots providing tabs 15 which, in the assembled position of the sheets, are received within corresponding slots 12 in the spacers 11. Thus each of the envelopes 10 is formed of four sheets 13 each extending in overlapping, end-to-end relationship parallel to and in spaced relationship with the side walls of the inner and outer walls of the cabinet. The adjacent ends of the sheets 13 of each of the envelopes 10 extend within the slots 12 and overlap each other as indicated at 16. The ends are secured to each other in any suitable manner, as by gluing, and may also be secured to the adjacent portion of the corresponding spacer 11. Alternatively, the gluing of the sheets 13 to the spacers may be omitted, affording some sliding movement of the envelopes 10 relative to the spacers and permitting the spacers to adjust themselves more readily to variations in cabinet size.

Referring to Fig. 1, it can be seen that, in the assembled position, the insulating structure 9 extends beyond the overlapping flange 6 and the structure could not be inserted through the opening in the outer walls 2. However, by making the spacers of hollow inflatable construction in accordance with my invention, the insulating structure may be partially collapsed to facilitate insertion of the structure within the cabinet through the opening in the outer wall. To facilitate the inflating and deflating of the spacers 11, each of the spacers is provided with a valve 17 for entry of air into and withdrawal of air from the interior of the spacers 11. The spacers may be made so that they normally assume the expanded position shown in Fig. 6 and are collapsed upon withdrawal of air from the interior of the spacers. Alternatively, the spacers may normally assume a collapsed position and be moved to the expanded position illustrated in Fig. 6 upon the supplying to the interior of the spacers a pressure exceeding atmospheric.

In either case, in carrying out my invention the insulating structure, including the spacers 11 and the envelopes 10, is first assembled on the exterior of the inner wall or liner 3 to form a unitary structure for insertion within the outer wall 2. The insulating structure is then partially collapsed to the position illustrated in Fig. 4 and in greater detail in Fig. 3, for example by withdrawing air from the spacers through the valves 17. The resultant partial collapse of the spacers 11 moves the concentric envelopes 10 toward each other reducing the cross-sectional area of the combined liner and insulating structure assembly so that it may readily be inserted through the opening in the outer wall. After the liner and insulating structure has been received within the interior of the outer wall 2, the valves 17, which are readily accessible from the top of the cabinet, are opened allowing air to enter the spacers 11, effecting an expansion of the spacers 11 and of the overall insulating structure to the condition shown in Fig. 1. Thus, the liner and insulating structure are readily inserted in the pre-assembled condition through the opening in the outer wall and, after such assembly, the insulating structure is readily expanded so as to distribute the envelopes 10 in evenly spaced concentric relationship between the inner and outer walls.

The structure described above is applied to the side walls of the liner 3, since this particular portion of the structure is that which introduces the greatest difficulty in assembly. An insulating structure which also uses spaced sheets of a material of high reflectivity, such as aluminum foil, is also employed in the bottom of the cabinet 1. However, since this bottom structure may readily be inserted at an angle through the opening in the outer wall, the hollow inflatable spacers are not employed. In lieu of these spacers a frame 18 of the material of low heat conductivity is provided extending along the perimeter of the interior of the wall 2. The frame 18 is provided with a plurality of spaced slots for receiving sheets 19 of a material of high reflectivity, such as aluminum foil, and maintaining these sheets in proper spaced relationship. In order that the bottom insulating structure may interfit with the insulating structure assembled on the liner, the frame is chamfered or beveled as indicated at 20.

While I have shown and described a specific embodiment of my invention, I do not desire my invention to be limited to the particular construction shown and described and I intend by the appended claims to cover all modifications within the spirit and scope of my invention.

What I claim as new and desire to secure by Letters Patent of the United States is:

1. An insulating structure for a spaced wall cabinet comprising a plurality of concentric envelopes adapted to be disposed between the spaced walls thereof, each of said envelopes including a plurality of sheets of a pliant material of high reflectivity arranged in end to end relationship, a plurality of hollow inflatable spacers arranged in spaced relationship and transversely with respect to said sheets, each of said spacers having a plurality of spaced slots therein, each of said sheets having a tab at each end received within a corresponding one of said slots, the tabs of adjacent sheets of each envelope overlapping each other and being secured to each other, and means for affording deflation of said spacers to

partially collapse said structure for facilitating insertion thereof in the cabinet.

2. An insulating structure for a spaced wall cabinet comprising a plurality of concentric rectangular envelopes adapted to be disposed between the spaced walls thereof, each of said rectangular envelopes including a sheet of pliant material of high reflectivity forming each side thereof, a hollow inflatable spacer at each corner of said envelopes, each of said spacers having a plurality of spaced slots therein, each of said sheets having a tab at each end received within a corresponding one of said slots, the tabs of adjacent sheets of each envelope overlapping each other and being secured to each other, and means for affording deflation of said spacers to partially collapse said structure for facilitating insertion thereof in the cabinet.

3. An insulating structure for a spaced wall cabinet comprising a plurality of concentric rectangular envelopes adapted to be disposed between the spaced walls thereof, each of said rectangular envelopes including a sheet of a pliant material of high reflectivity forming each side thereof, a hollow inflatable spacer diagonally positioned at each corner of said envelopes, each of said spacers having a plurality of spaced slots therein, each of said sheets having a tab at each end received in a corresponding one of said slots, the tabs of adjacent sheets of each envelope overlapping each other and being secured to each other, and means for affording deflation of said spacers to partially collapse said structure for facilitating insertion thereof in the cabinet.

4. A structure for insertion within the outer wall of a spaced wall cabinet comprising an inner wall, a plurality of sheets arranged to form a plurality of concentric envelopes surrounding said inner wall, each of said sheets being composed of a pliant material of high reflectivity, a plurality of hollow inflatable spacers secured to said inner wall for holding said sheets in spaced relationship, and means for affording deflation of said spacers to partially collapse said structure for facilitating insertion thereof in the cabinet.

5. In a spaced wall cabinet including an inner wall and an outer wall having an opening therein smaller than said cabinet, the method of insulating said cabinet which consists in providing a unitary insulating structure including a plurality of spaced parallel sheets of a pliant material of high reflectivity and hollow inflatable spacers having portions interposed between adjacent pairs of sheet for holding said sheets in spaced relationship, deflating said spacers to partially collapse said structure, inserting said structure within said outer wall through said opening, and thereafter inflating said spacers for expanding said structure to fill the space between said walls.

6. In a spaced wall cabinet including an inner wall and an outer wall having an opening therein smaller than said cabinet, the method of insulating said cabinet which consists in providing a unitary insulating structure including a plurality of spaced parallel sheets of a pliant material of high reflectivity and hollow inflatable spacers having portions interposed between adjacent pairs of sheets for holding said sheets in spaced relationship, evacuating said spacers to partially collapse said structure, inserting said structure within said outer wall through said opening, and thereafter allowing air to enter said

spacers for expanding said structure to fill the space between said walls.

7. In a spaced wall cabinet including an inner wall and an outer wall having an opening therein smaller than said cabinet, the method of insulating said cabinet which consists in providing a unitary insulating structure including a plurality of spaced parallel sheets of a pliant material of high reflectivity and hollow inflatable spacers having portions interposed between adjacent pairs of sheets for holding said sheets in spaced relationship, allowing air to escape from said spacers to partially collapse said structure, inserting said structure within said outer wall through said opening, and supplying air to said spacers for expanding said structure to fill the space between said walls.

8. A cabinet comprising spaced outer and inner walls forming a storage compartment having an opening on one side thereof, said outer wall having an inwardly extending flange bordering said opening, an insulating structure mounted on the outer surface of said inner wall, said insulating structure including a plurality of sheets of pliant material of high reflectivity supported in spaced generally parallel relation to the respectively adjacent portions of said inner wall, a plurality of hollow inflatable spacers mounted on said inner wall constructed and arranged to support and maintain said sheets in spaced generally parallel relation between adjacent portions of said inner and outer walls, each of said spacers including a plurality of spaced supporting portions, each of said supporting portions being in contact with and supporting a portion of one of said sheets, and means for affording deflation of said spacers to partially collapse said insulating structure against said inner wall for facilitating insertion of said inner wall and said structure through the opening defined by said inwardly extending flange.

9. A cabinet comprising spaced outer and inner walls forming a storage compartment of rectangular cross-section having an opening on one side thereof, said outer wall having an inwardly extending flange bordering said opening, an insulating structure mounted on the outer surface of said inner wall, said insulating structure including a plurality of sheets of a pliant material of high reflectivity supported in spaced generally parallel relation to the respectively adjacent portions of said inner wall, a plurality of hollow inflatable spacers mounted on said inner wall and extending diagonally from the corners of said wall, said spacers being constructed and arranged to support and maintain said sheets in spaced generally parallel relation between adjacent portions of said inner and outer walls, each of said spacers including a plurality of spaced supporting portions, each of said supporting portions being in contact with and supporting a portion of one of said sheets, and means for affording deflation of said spacers to partially collapse said insulating structure against said inner wall for facilitating insertion of said inner wall and said structure through the opening defined by said inwardly extending flange.

10. A cabinet comprising spaced outer and inner walls forming a storage compartment having an opening on one side thereof, said outer wall having an inwardly extending flange bordering said opening, an insulating structure mounted on the outer surface of said inner wall, said insulating structure including a plurality of envelopes spaced concentrically with respect to said inner

wall, each of said envelopes comprising a plurality of sheets of a pliant material of high reflectivity arranged in end to end relationship, a plurality of hollow inflatable spacers mounted in spaced relationship on said inner wall, each of said spacers having a plurality of spaced slots therein, each of said sheets having a tab at each end received within a corresponding one of said slots, the tabs of adjacent sheets of each envelope overlapping each other and being secured to each other whereby said envelopes are supported in spaced relationship on said spacers, and means for affording deflation of said spacers to partially collapse said structure against said inner wall for facilitating insertion of said inner wall and said structure through the opening defined by said inwardly extending flange.

11. An insulating structure for a spaced wall cabinet comprising a plurality of parallel sheets composed of a pliant material of high reflectivity, a plurality of hollow inflatable spacers for supporting said sheets in spaced relationship between and parallel to adjacent spaced walls of said cabinet, each of said spacers having a number of spaced supporting portions corresponding to the number of said sheets, portions of each of said sheets being directly secured to corresponding portions of said spacers, and means affording deflation of said spacers to partially collapse said structure for facilitating insertion thereof between adjacent spaced walls of said cabinet.

12. A structure as defined by claim 11 in which the pliant material of high reflectivity is aluminum foil.

13. A structure as defined by claim 11 in which the means affording deflation of each of the spacers includes a valve communicating with the interior thereof.

14. An insulating structure for a cabinet of the type having spaced inner and outer walls enclosing a storage compartment, said structure comprising a plurality of concentric envelopes of a configuration generally corresponding to that of the inner and outer walls of said cabinet, each of said envelopes being formed from a sheet of a pliant material of high reflectivity and having a

plurality of plane surfaces and a corresponding number of corners, a plurality of hollow inflatable spacers for holding said envelopes in spaced relationship, said spacers being diagonally arranged in supporting contact with the corners of said envelopes, each of said spacers including a plurality of spaced supporting portions, each of said supporting portions being in contact with and supporting a corner portion of one of said envelopes, and means for affording deflation of said spacers to partially collapse said structure for facilitating insertion thereof between the spaced inner and outer walls of said cabinet.

15. An insulating structure for a cabinet of the type having spaced inner and outer walls enclosing a storage compartment of rectangular cross-section, said structure comprising a plurality of concentric rectangular envelopes adapted to be disposed between the spaced walls of said cabinet in generally parallel relation with adjacent portions of said walls, each of said envelopes including a sheet of a pliant material of high reflectivity forming each of the four sides thereof, the adjacent ends of the four sheets forming each of said envelopes being secured together at the corners thereof, a plurality of hollow inflatable spacers for holding said envelopes in spaced relationship, said spacers being arranged in supporting contact with the corners of said envelopes, each of said spacers including a plurality of spaced supporting portions, each of said supporting portions being in contact with and supporting a corner portion of one of said envelopes, and means for affording deflation of said spacers to partially collapse said structure for facilitating insertion thereof between the spaced inner and outer walls of said cabinet.
